(57) **CLAIM**

The ornamental design for a virtual reality headset, as shown and described.

DESCRIPTION

1. Virtual reality headset

1.1 is a top, front perspective view of a virtual reality headset showing the claimed design;

1.2 is a top view thereof;

1.3 is a bottom view thereof;

1.4 is a front view thereof;

1.5 is a rear view thereof; and

1.6 is a right side view thereof.

The broken lines and areas inside the broken lines in FIG. 1.3 and FIG. 1.5 form no part of the claimed design.
